UNITED STATES PATENT OFFICE.

JULIAN H. RIVERS, OF ST. LOUIS, MISSOURI, ASSIGNOR, BY MESNE ASSIGNMENTS, TO
UNIVERSAL FIBRE COMPANY, OF NEW YORK, N. Y., A CORPORATION OF DELA-
WARE.

PROCESS OF COMPACTING FIBROUS AND OTHER PARTICLES.

1,174,180.

Specification of Letters Patent.

Patented Mar. 7, 1916.

Application filed August 28, 1905, Serial No. 276,179. Renewed July 26, 1915. Serial No. 42,070.

To all whom it may concern:

Be it known that I, JULIAN H. RIVERS, a citizen of the United States, residing at St. Louis, Missouri, have invented a new and useful Process of Compacting Fibrous and other Particles, of which the following is a specification.

This invention relates to the process of compacting fibrous and other particles into shaped objects, and has for its object to produce a process by which materials suspended in liquid can be compacted into objects of various sizes and shapes, without the aid of mechanical pressure.

15 In following this process I commence at that point where the desired amounts and proportions of the fibrous and other materials to be compacted are already aggregated, so that by stirring or agitating the liquid 20 containing them they may be thoroughly diffused as required for the best final results.

I will explain the various stages and results in the process in connection with an 25 approved form of machine for shaping articles of one class, as shown in the drawings which form part of this specification, stating, however, that the process can be followed with equal satisfaction in producing 30 various other articles, all of which will be readily understood by those skilled in this art.

In the drawings Figure 1 is a vertical sectional view of a machine for producing 35 boxes by my new process. Fig. 2 is a side elevation thereof, with part of the framework broken away in order better to show some of the essential parts. Fig. 3 is a view of the under side of the bottom of the container and former. Fig. 4 is a section thereof, and Fig. 5 shows the construction of the supporting wall of the former.

The structural features of the machine 45 illustrated, which are involved in the practice of the invention, comprise a tank or container 1 having an inlet 2 through which the fibrous and other materials to be compacted, and the liquid or a portion thereof may be fed. The inlet should be provided 50 with means for closing, such for instance as the float valve 3, which will be forced to close

position whenever the tank or container becomes filled. The bottom 4 of the container is concave and has an opening 5 through which the contents may pass to the former 55 or formers, supported underneath. The former shown consists of the perforated side plates 6 attached to hinged supports 7. Across the inner faces of said supports are formed V-shaped grooves 8 and at right 60 angles thereto on the outer faces of said supports similar grooves 9 are formed, said grooves being of sufficient depth to form holes 10. The supports 6 are attached to the plates 11 which are hinged at 12 so that 65 they may be swung outward at times. Toggle connection 13 may be utilized to control and brace the sides in operative position.

A vertically movable bottom is supported by any approved arrangement below the 70 sides 6. This bottom is of the same construction as the sides, consisting of a perforated plate or screen 14 and a grooved and perforated support 15. The latter is attached to supporting members 16 operating 75 through guides 17 and connected at their lower ends to a shaft 18 which is upheld by links 19 carried by a shaft 20 on the lower ends of the links 21, suspended by the frame of the machine. The ends of the shaft 18 80 operate in guides 22. By swinging the shaft 20 outward as indicated by dotted lines in Fig 1, the bottom will be lowered a sufficient distance to permit removal of the article compacted in the formers. 85

23 indicates a valve controlled inlet through which additional liquid may be injected into the container. This inlet enters, preferably, near the bottom, and is injected obliquely upward, (Fig. 1), so that liquid 90 entering therethrough will agitate and assist in diffusing the contents of the container without creating or causing descending currents. It is desirable to avoid the action of descending currents during agitation, so 95 that even deposition against the sides and bottom of the former or formers, of an advance or first portion of the fibrous material may occur, as presently described. Currents passing into or through the former or 100 formers, would obstruct even deposition and would cause bulking of the mass.

In practice the fibrous and other material or materials, mixed with more or less liquid, are put into the container through the inlet 2, and at the same time liquid is injected into the container through the inlet 23, the flow thereof continuing until the container is nearly full, or until the valve 3 is closed. The stream of liquid so injected agitates the contents and causes the materials that are to be compacted to become thoroughly diffused. As soon as the materials are put into the container the liquid commences to flow through the perforated sides and bottom of the former with nearly equal speed and this movement and escape of the liquid results in the deposit of some of the fibrous material against the sides and bottom, the perforations therein being too small to permit passage of said material. The fibers being thus laid across the holes stop the material following, as the liquid flows, or is forced, through the former.

After the container has been filled, and after a portion of the material has been deposited against the walls and bottom of the perforated former compressed air or steam is admitted into the container, preferably above the contents, through an inlet 24. The intrushing air or steam, because of its natural tendency to expand, quickly and forcefully drives all the liquid through the perforated former, and the liquid carries the fibrous and other material into the said former and evenly compacts and felts the same therein, the walls and bottom of the former shaping the exterior of the product. If light substances alone are to be compacted, the water or liquid entering through the pipe 23 will cause approximately even diffusion of such substances. If heavy substances are included, the liquid nearer the top of the container will be somewhat clearer than that at the bottom. Heavy and light particles, such as fibrous pulp and powdered, pulverized or comminuted cements or other minerals may be mixed together to form a composite article, in which case the pulp will be nearly evenly distributed in the liquid while the mineral substances will be heaviest near the bottom. In such case the pulverized or triturated cement in the finished product will be densest near the surface first formed while the greatest quantity of pulp will be toward the surface last formed, but there will be no stratification or formation of layers. This is the structure of highest efficiency for many articles such as boxes which are subject to frequent handling and the exterior of such articles should be the first formed. The air or steam pressure is continuous until all of the water is driven out through, and all of the other material into, the perforated former. Then the air or steam is cut off and the product removed from the

former by lowering the bottom upon which the product rests, the sides at the same time swing outward on their hinged supports in order to give free movement. The product may then be removed manually from the bottom and the latter returned to closed position when the machine is ready for further use.

It will be observed that the aeriform fluid of compression used in this process presses from behind the flowing water, thereby driving the flowing water through the "former" or mold and through the materials being compacted or felted therein and thereon. By this method or process of compacting, much greater density in the product is attained than can be attained by those processes wherein suction is employed to draw out the water. The atmospheric weight is fifteen pounds per square inch of surface, so that when suction is used it only permits the air to drive the water with about fifteen pounds pressure per square inch of surface. That is about the maximum pressure that can be imparted by suction, because the uncompressed air compresses or bears against any surface with about its own weight. By admission from above the materials the air, or steam, or other aeriform fluid can be made to eject the water under pressure many times the pressure obtainable by suction, and thereby produce finished articles of much greater density, and more free from water or saturation. I have discovered that when suction is used much more water remains in the mass of compacted material than when the water is driven out by controlled aeriform fluid from behind. In the case of suction being used, when the suction is stopped, the pulp acts with a powerful suction so that any water remaining near the mass is at once drawn back and reabsorbed. It requires from thirty to forty pounds of pressure behind the water and through the mass to overcome this reabsorption, and to produce articles compacted with sufficient solidity and density to dispense with the requirement of subsequent mechanical pressure. Therefore, by the controlled aeriform fluid pressure from behind the water, a superior article, of greater density, and containing a minimum quantity of water, is produced, said article being of sufficient density to dispense with the need of mechanical pressure for completion.

While I have shown a machine having a capacity of shaping or forming one article at a time, it is obvious that machines may be used which have a plurality of formers, and that many articles may be produced at each operation. After removal, the articles may be subjected to heat or chemical treatment, though this may be found inessential in many instances.

The process may be varied in minor limits without change of result or of quality of the product, and hence without restricting myself to unnecessary steps,

5. What I claim as new and desire to secure by Letters Patent is:

1. That process of molding liquid-borne particles into shaped articles, which consists in injecting a flow of clear liquid into the 10 liquid containing the particles effectively to increase the quantity of liquid in proportion to the particles borne therein and to agitate and make even distribution of the particles through the increased quantity of 15 liquid, simultaneously depositing a thin layer of the particles against a perforated "former" outside the zone of agitation, and then applying a high steam pressure behind the liquid effectively to drive the liquid 20 through the perforated "former" and through the particles deposited thereagainst, substantially as specified.

2. That process of molding fibrous pulp, which consists in injecting a flow of liquid 25 into the pulp effectively to agitate and diffuse the pulp, simultaneously causing the liquid to flow through, and deposit a thin layer of the pulp against, a perforated "former" outside the zone of agitation, and 30 then stopping the agitation and simultaneously applying high steam pressure behind the liquid effectively to drive all the liquid through the perforated "former" and through the pulp deposited thereagainst, 35 substantially as specified.

3. The herein described method of making articles, which consists in putting a mixture of cement and water in a pressure chamber, admitting additional water to said 40 mixture in said chamber before the solids of the mixture have settled and then increasing the pressure in the chamber above the liquid effectively to deposit the solid matter upon the "former" or mold and press 45 the water out therethrough, substantially as specified.

4. The method of forming articles, which consists in placing a mixture of cement and water upon the mold or "former" of a pressure 50 chamber, admitting an additional quantity of water into said chamber before the solids of the mixture have settled, and then admitting aeriform fluid under increasing pressure to the chamber until the 55 desired pressure is secured, substantially as specified.

5. The method of forming articles, which consists in placing a mixture of fibrous material and cement and water upon the mold 60 or "former" of a pressure chamber, admitting an additional quantity of water into said chamber before the solids of the mixture have settled, and then increasing the pressure in the chamber above the fluid to deposit the cement and fibrous material 65

upon the mold or "former" and press the water out therethrough, substantially as specified.

6. The method of forming articles, which consists in placing a mixture of cement and water upon the mold or "former" on the bottom of the chamber, admitting a quantity of water upwardly into said chamber, and then admitting aeriform fluid under pressure to the chamber above the water to 70 deposit the cement on the "former" and press the water out therethrough, substantially as specified. 75

7. The method of forming articles, which consists in placing a mixture of fibrous material and cement and water in a pressure chamber above the mold or "former," admitting additional water into said chamber below the level of the mixture, permitting primary flow of the mixture through 80 the mold or "former" effectively to deposit a relatively thin layer of the fibrous material and cement on the "former" and then increasing the pressure in the chamber above the mixture effectively to deposit the remaining fibrous material and cement upon 85 said relatively thin layer and press the water out therethrough, substantially as specified. 90

8. The method of making articles, which 95 consists in placing a mixture of fibrous material and powdered solids and water upon the "former" of a pressure chamber, admitting an additional quantity of water to the chamber above said "former" and below the 100 level of said mixture before the solids of the mixture have settled, and admitting steam under pressure to the chamber above the mixture and "former" to deposit the fibrous material and solids upon the 105 "former" and press the water out therethrough.

9. That process of molding liquid-borne particles into shaped articles, which consists in injecting a flow of liquid into and below the level of the liquid containing the particles, effectively to increase the quantity of liquid in proportion to the particles borne therein and to agitate and make even distribution of the particles through the increased quantity of liquid, depositing a thin layer of the particles against a perforated "former" outside the zone of agitation by causing a flow of the liquid through said "former" and then after said thin layer has 110 been formed, applying a high aeriform pressure behind the liquid and particles effectively to drive the liquid against the perforated "former" and through the particles deposited thereagainst, substantially as specified. 115 120

10. The method of forming articles which consists in placing a mixture of fibrous materials and water within a mold at the bottom of a pressure chamber, permitting a 130

4
quantity of the water to flow, by gravity,
through the side and bottom walls of the
mold, and then admitting steam under
pressure to the chamber above the mixture
5 to deposit the fibrous materials on the mold
and press the water out therethrough, sub-
stantially as specified.

In testimony whereof I hereto affix my
signature in the presence of two witnesses.
